(57) **CLAIM**

The ornamental design for a tire pressure gauge, as shown and described.

DESCRIPTION

FIG. 1 is a perspective view of a tire pressure gauge showing our new design, according to an embodiment of the invention;

FIG. 2 is a top view of the tire pressure gauge of FIG. 1;

FIG. 3 is a bottom view of the tire pressure gauge of FIG. 1;

FIG. 4 is a right side elevational view of the tire pressure gauge of FIG. 1;

FIG. 5 is a left side elevational view of the tire pressure gauge of FIG. 1;

FIG. 6 is a front elevational view of the tire pressure gauge of FIG. 1;

FIG. 7 is a rear elevational view of the tire pressure gauge of FIG. 1;

FIG. 8 is a top view of the tire pressure gauge of FIG. 1, shown in use with an energized exemplary display; and,

FIG. 9 is a perspective view of a tire pressure gauge, showing our new design, according to another embodiment of the invention.

The matter shown in dashed lines is environmental structure and forms no part of the claimed design.
